PIN MOUNTING

Louis F. Parr, Chicago, Ill., assignor to Eugene Dietzgen Company, Chicago, Ill., a corporation of Delaware

Application December 31, 1934, Serial No. 759,936

6 Claims. (Cl. 33—152)

My invention relates in general to drawing and measuring instruments and the like and has more particular reference to novel means for mounting pointed pins more especially on compasses, dividers, et cetera.

An important object is to provide an adjustable mounting for pointed pins and the like whereby the pin is not touched in adjusting the same and possibility of injury to the pin or to the person accomplishing the adjustment is avoided.

Another object is to provide an adjustable mounting for pointed pins wherein the pin may be adjusted and secured in adjusted position by controlling common adjusting and clamping means.

Another object is to provide a pin shifting and clamping device more especially adapted to mounting a pointed pin as on the leg of a compass or divider.

Another object is to provide a pin mounting including a clamping element manually operable to secure the pin in adjusted position, the clamping element being also operable to shift the pin longitudinally in order to adjust the same on the mounting.

Another object is to utilize a formed plate to frictionally secure the pin on the clamp so that the same may be shifted longitudinally by manipulation of the clamp.

Numerous other objects, advantages, and inherent functions of the invention will become apparent as the same is more fully understood from the following description, which, taken in connection with the accompanying drawing, discloses a preferred embodiment of the invention.

Referring to the drawing:

Figure 1 is a partial view of a drawing instrument provided with a pin mounting embodying my present invention;

Figure 2 is an enlarged sectional view taken substantially along the line 2—2 in Figure 1;

Figure 3 is an exploded view of the several parts forming the pin mounting; and

Figure 4 is a sectional view taken substantially along the line 4—4 in Figure 2.

To illustrate the invention, I have shown on the drawing an instrument 11, which may be a compass, divider, or other instrument, on which is mounted a pointed pin 13. The instrument shown has a leg 15, on which the pin 13 is adjustably supported by means of a mounting embodying my present invention. The instrument also has another leg 17, which carries a marking device, where the instrument is used as a compass, or another pointed pin, where the instru-

ment is to function as a divider. It may be necessary to adjust the position of the pointed pin 13 on the leg 15, particularly where the instrument 11 comprises a compass, in which the scribing device on the leg 17 may become worn off necessitating adjustment of the pin 13 on the leg 15 in order to compensate for such wear.

I have provided a mounting by means of which the pin may not only be secured on the leg 15 but also may be adjusted thereon without the necessity of touching the pin during adjustment. The mounting moreover permits adjustment of the pin and clamping of the same in adjusted position simultaneously. To this end, the leg 15 is provided with an elongated opening 19, 15 terminating short of the end of the leg. The inner face of the leg is provided with a groove 21 extending from the end of the opening 19 to the end of the leg.

The clamping and adjusting device comprises 20 a bolt 23 having screw threads at one end for the reception of a clamping nut 25, the bolt at its opposite end being provided with a diametral opening 27 of a size sufficient to receive the pin 13 therein. The bolt 23 is mounted on the leg in 25 position extending through the opening 19 with the threaded portion of the bolt carrying the nut 25 extending on one side of the leg, the perforated portion of the bolt carrying the pin 13 extending on the opposite side of the leg. The pin 13, when 30 so mounted, has an end extending in the groove 21, the tip of the pin projecting outwardly of the end of the leg. In order to permit the pin to be clamped securely on the leg by tightening the nut 25, I provide a clamping plate 29 having a 35 central, preferably U-shaped groove 31 and flanges 33. This plate also has a central perforation 35 in the groove 31, said perforation being large enough to accommodate the bolt 23. The plate 29 is assembled on the bolt behind the pin 40 27 so that the pin lies in the groove 31, the plate portions forming the groove extending in the opening 19 and the flanges 33 of the plate riding and bearing on the surfaces of the leg portions defining the opposite sides of the slot 19. 45 If desired, a washer 37 may also be assembled on the bolt 23 between the facing surfaces of the nut 25 and the leg.

It will be seen that when the nut 25 is screwed 50 down tightly on the bolt 23, the bolt will be drawn through the opening 19 in a direction to seat the pin 27 tightly in the groove of the plate 29 and also to seat the marginal flanges of the plate tightly on the leg so that the pin will be fric- 55

tionally held against longitudinal movement with respect to the leg. By loosening the nut 25 on the bolt, the frictional engagement between the plate flanges and the leg may be reduced sufficiently to permit the entire assembly to be moved longitudinally on the leg by applying pressure in the desired direction on the nut 25 and without disturbing the relative position of the pin in the bolt, the frictional engagement of the pin with the plate serving to hold the pin in place in the bolt during the longitudinal adjustment. The pin is thus carried with the bolt and may be adjusted on the leg to any desired position without being directly touched. When the pin is in a desired adjusted position with respect to the leg, it may be clamped in place simply by tightening the nut 25.

While I have shown an instrument of the so-called "bow" type, it will be obvious that the invention is not necessarily restricted to the particular form of instrument illustrated but may be applied to any instrument in which an adjustable needle point mounting is required. The nut and bolt may, of course, be made of any suitable preferably metallic material in any convenient manner as on a screw machine and the leg, pin, and washer may likewise be fashioned in any suitable or preferred form or manner. The clamping plate 29 also may be fashioned from suitable material, preferably sheet metal, by a simple punching or stamping operation.

The adjustable clamp of my present invention has the advantage that it permits adjustment of the pointed pin or needle 13 without touching the same and thus eliminates danger of either damaging the point or injuring the person accomplishing the adjustment. The adjustable clamp mounting has the further advantage that adjustment and clamping are accomplished by the single operation of manipulating the clamping nut 25.

It is thought that the invention and numerous of its attendant advantages will be understood from the foregoing description and it is obvious that numerous changes may be made in the form, construction, and arrangement of the several parts of the illustrated apparatus without departing from the spirit or scope of my invention or sacrificing any of its attendant advantages, the preferred modes and forms herein described being merely for the purpose of illustrating the invention.

Having thus described my invention, what I claim as new and desire to secure by Letters Patent is as follows:

1. The combination with a support element having an elongated slot, of means for adjustably mounting a pin on said element, said means comprising a member extending in the slot and longitudinally movable therein and having ends projecting on opposite sides of the support element, one of said ends having an opening for the reception of the pin whereby the same may be supported on one side of said element and shifted thereon with said member, and clamping means comprising a plate held on one end of said member by said pin in position to engage one side of the support element, and a clamp co-operatively associated with the other end of said member in position to co-operate with the opposite side of the support element whereby to clampingly secure the pin on said plate and to clamp said support element between the plate and the clamp solely by the manipulation of said clamp. 10 15

2. The combination as set forth in claim 1, wherein said plate is formed with a groove for the reception of said pin. 20

3. The combination as set forth in claim 1, wherein said member comprises a bolt having a threaded portion and the clamp comprises a nut co-operatively associated with the threaded portion of said bolt. 25

4. The combination as set forth in claim 1 wherein the element on one side thereof is formed with a groove at the end of the slot, the groove being adapted to receive and prevent lateral movement of the pin with respect to the support element. 30

5. The combination with a support element, of means for adjustably mounting a pin thereon, said means comprising a stem having a diametral opening in an end thereof, said stem being longitudinally shiftable on said element, a resilient plate on said stem and clamping means to secure the stem on the support element and draw the resilient plate against the support element whereby to yieldingly secure the pin in said diametral opening. 35 40

6. The combination with a support element having a longitudinal groove therein forming a pin seat, of means for adjustably mounting a pin on the support element in position extending in said groove, said means comprising a stem having a diametral opening in an end thereof, said stem being longitudinally shiftable on said element, a resilient plate on said stem and clamping means to secure the stem on the support element and to draw the resilient plate against the support element whereby to yieldingly secure the pin in said diametral opening and on said seat. 45 50 55
